UNITED STATES PATENT OFFICE.

BIRGER T. ANDREN, OF MILWAUKEE, WISCONSIN, ASSIGNOR TO A. O. SMITH CORPORATION, OF MILWAUKEE, WISCONSIN, A CORPORATION OF NEW YORK.

MOVABLE PLATFORM FOR POSITIONING SPECIAL MACHINES AND TOOLS.

1,408,156.

Specification of Letters Patent. Patented Feb. 28, 1922.

Application filed March 5, 1921. Serial No. 450,074.

To all whom it may concern:

Be it known that I, BIRGER TORVALD ANDREN, a subject of the King of Sweden, (but who has declared his intention of becoming a citizen of the United States,) and a resident of the city of Milwaukee, county of Milwaukee, and State of Wisconsin, have invented certain new and useful Improvements in Movable Platforms for Positioning Special Machines and Tools; and I do declare the following to be a clear, exact, and complete description thereof, such as will enable persons skilled in the art to which the invention pertains to make and use the same, reference being had to the drawings accompanying this specification for a disclosure of one construction in which my invention has been embodied.

My invention relates to a movable platform upon which are mounted certain machines and tools designed for the performance of special operations, for instance, such as take place in uniting the assembled elements of an automobile or other vehicle frame, and by means of which movable platform the special machines and tools may be brought into and out of position with relation to the assembled frame elements upon which they are constructed and arranged to operate in effecting such union.

In the plant of the assignee corporation, such frames are manufactured automatically. The side bars and cross bars, and other structural elements of the frame, are progressively blanked, pierced and shaped, and then assembled in the relative positions which they occupy in the completed frame. The assembly of the elements is in or upon a traveling carrier or conveyor jig, which presents such elements in position for the machines or tools to perform the special operations of reaming the holes formed in the juxtaposed elements at the points where the union of the parts is to be effected, inserting rivets in the said holes, and spreading the rivets so as to unite the elements into a rigid and unitary structure, the said machines and tools also performing such other special operations as may pertain to the particular type of frames then being manufactured.

In a prior application filed by R. Stanley Smith, on January 21, 1918, Serial No.

212,934, and patented November 15, 1921, No. 1,397,020, there is disclosed an assemblage of machines which by their related, connected and successive operations, punch from sheet metal plates and strips the side and cross bar and other blanks used in the construction of an automobile or other vehicle frame, shape such blanks into channels or otherwise according to the particular requirements and purposes appertaining to each, perform the necessary milling or machining operations thereon, assemble the several constituent elements of the frame in their relative positions, and secure all of such elements in their respective final positions by means of rivets, or other means of fastening, so that in a continuous operation of mechanical devices a completed automobile or other vehicle frame is automatically produced. The several operations of the machines comprised in the assemblage referred to occur in sub-divided time cycles, a portion of each time cycle being allotted for the simultaneous performance of the successive machining operations, followed by a conveyor movement of the frame elements during the remainder of the time cycle, to advance the elements for the performance of the next succeeding series of operations constituting steps in the process of manufacturing a completed frame. The assemblage as a whole is thus operated upon a time schedule which provides for the automatic production of a given number of completed automobile frames per minute during the operation of the assemblage.

The jigs before referred to as supporting and conveying the assembled frame elements, pass along a line upon each side of which are located the several stations at which the several machines and tools are arranged. The number of such stations and the number of machines or tools located thereat, are factors which will be determined by the type or character of the particular frame which the assemblage is organized to produce.

I have found it conducive to the production of the desired results to mount the special machines and tools upon platforms or bases, which latter with the machines and tools supported thereon, may have capacity for movement toward the line along which

the conveyor jigs pass, so that the said special machines and tools may be brought into the positions which they occupy at the time of the simultaneous performance of their progressive mechanical operations upon the assembled frame elements. Conversely, the platforms with said machines and tools are retracted at the conclusion of the mechanical operations, so that the conveyor movement 10 of the carrier jigs may take place without interference from the machines and tools previously moved to working positions. The conveyor movement of the jigs is step-by-step from station to station, in the intervals between the work performing operations of the special machines and tools, and while such machines and tools are in their retracted and inoperative positions of rest. In former constructions, the special machines and tools have been mounted upon relatively fixed pedestals or bases, the latter having provisions for adjustment with relation to the line of the work. In such older forms of the apparatus, it has been necessary to provide as a part of the construction of each special machine and tool, some means for moving the work performing devices of such machines and tools into position for operation upon the assembled frame elements, after the conveyor jig has brought the latter into a correct position of registry in the line of its travel. A material constructional advantage resides in my present plan of mounting the special machines and tools so as to be bodily movable into and out of the fields of their operation, in that such plan largely eliminates the necessity for the provision of the moving parts in each formerly fixed special machine or tool for positioning the work performing devices thereof with relation to the work, prior to the actual operation of such devices.

My invention comprises a movable platform, designed, as before stated, for the purpose of supporting machines and tools employed in the performance of certain special operations connected with the uniting of assembled, but as yet unattached, automobile frame elements into a permanent structure. The machines and tools are adjustably positioned upon the said platform, and partake of the movements of the latter toward and from the line of the work. The platform is of considerable length, and is composed of a plurality of sections or units preferably connected or operated so as to be moved as one part. Hence, one movement of the long platform will accurately position all of the machines and tools which have been mounted thereon and adjusted for operation, and when so positioned by the movement of the platform upon which they are mounted, the several machines and tools will be actuated for the simultaneous performance of their predetermined progressive

operations. Following the retirement of the machines and tools after performing their allotted work, the conveyor jigs, each loaded with an assembled set of frame elements, which latter are progressively united in the intervals of the step-by-step feeding movement of the conveyor jigs, are moved so as to present the assembled frame elements at other stations on the line for the succeeding operations. The machines and tools at the several stations are each equipped and adjusted for the performance of a particular operation, so that in the progression the devices employed severally perform their different operations simultaneously, and their like operations successively.

The movable elongated platform is arranged below the plane of the surface of the floor, and reciprocates laterally in a channel or pit beneath a grid structure, the slots in which extend parallel to the line of movement of the platform. Connection between the special machines and tools and the movable platform is made through the slots in the grid, so that the platform and the machine and tools carried thereby will move together, when the platform is reciprocated through the actuating means provided therefor.

The top surface of the grid is flush with the surface of the floor of the building, so that liability to personal injury is safely guarded. If a workman should stand on the grid within the area over which the special machines and tools move, his feet will not be caught, but will be slid over the grid in the backward or forward movements of the mechanisms, without injury to him. Likewise, the grid constitutes a safety cover for the channel or pit in which the moving platform operates, and so prevents the injury which might follow the accidental falling or stepping of a person into the said channel or pit, were the latter not covered by the grid mentioned.

Having thus outlined the general nature of my invention, I will now proceed to specifically describe the same, referring to the accompanying drawing as showing one of the forms in which the invention may be embodied, and particularly to the claims appended to this specification as defining the scope of my invention.

In the accompanying drawing, Figure 1 is a view partly in section and partly in elevation, on the line 1—1, Fig. 2, looking in the direction of the arrow, and showing the arrangement of the movable platform in a pit or channel below the plane of the surface of the floor.

Fig. 2 is a plan view of a section of the devices shown in Fig. 1, and showing particularly the arrangement of the grid as part of the floor formation.

Fig. 3 is a vertical sectional view on the

line 3—3, Fig. 1, looking in the direction of the arrow, and showing the manner in which connection is made through the slotted grid between the movable platform and the portable base for supporting one of the special machines or tools.

Referring now to the drawing, the floor 10 is constructed with a channel or pit 11, for the accommodation of the movable platform 12, the construction and arrangement of which will hereinafter, be described. The width of the channel or pit 11, will be such as to permit the necessary lateral movements or sidewise reciprocations of the platform 12, in advancing the special machines and tools to the line of the work, and their retraction therefrom, to take place.

The platform 12 conforms in its length to that of the line of travel of the conveyor carrying jigs, which latter are actuated intermittently in alternation with the work performing operations of the special machines and tools, as disclosed in the said application Serial No. 212,934, to advance the assembled frame elements from station to station along the line, for the progressive performance of the successive operations required to be executed by the several special machines and tools.

The platform 12 is composed of a plurality of sections or units, each of which in the existing construction, has a length of approximately 18 feet. The platform sections or units are coupled together at their contiguous ends, and are connected to their actuating mechanism in such manner that all of the sections are moved simultaneously with a parallel motion, and are actuated as would be an integral construction.

At spaced intervals in the length of the channel or pit, rail or track sections 13 extend transversely thereof. The platform sections or units 12 are provided at each end with flanged rollers 14 which ride upon the rail or track sections 13 to facilitate the reciprocatory movements of the platform sections or units. The said rollers 14 are journaled in the platform sections or units. The flanges of the said rollers by engaging the rails 13, serve to confine the platform sections to the path of their right line lateral movements, and so prevent any undue endwise movement of the platform sections.

The contiguous or meeting ends of the platform sections or units 12 are oppositely offset as shown in Fig. 2, and in each offset portion a pin 15 is fixed. A link 16 extending between the pins 15, serves to connect the platform sections or units, the said pins standing substantially in a line which is parallel to the path of movement of the platform. A slight clearance space, indicated 17 in Fig. 2, is provided between the contiguous ends of the platform sections or units, so as 60 to compensate for any slight irregularities

which may occur in the movement of the platform sections, due to expansion or contraction, or other causes, without affecting the position of other sections or units.

The channel or pit 11 is bridged by a series of transversely extending strips 18, arranged flush with the surface of the floor, the said strips being separated a fixed distance so as to form a grid, the principal purpose of which is to constitute a safety cover 75 for the channel or pit. The movable platform 12 reciprocates beneath the grid 18, and the open spaces between and by which the grid members are separated are utilized as a means through which the special machines and tools are attached to the movable platform, so as to be actuated thereby. In laying the floor, separated recesses 21, will be formed for the reception of the ends 80 of the bars 18 which constitute the grid. 85 The recesses 21 will be of such depth that the grid members, when placed therein, will be flush with the surface of floor leaving the latter entirely free from obstruction.

For convenience in mounting and supporting the special machines and tools in the desired positions upon the movable platform, as may be demanded by the requirements of the particular work, and the relative location of the points at which the work 90 is to be performed, I provide for each special machine or tool a portable base 19, which latter is formed at its underside with a series of depending parallel ribs 20, adapted to pass through the open spaces in the grid, 100 and rest upon the movable platform. The location of the special machines or tools with reference to the points at which the machine operations are to be performed having been determined, the portable base 19 will be positioned accordingly upon the platform section or unit 12, with the supporting ribs 20 passing through the slots of the grid. Any convenient means for uniting the portable base 19 to the movable platform section or 110 unit may be employed. However, I have found it convenient to form in the edges of the movable platform sections or units, a series of T-slots 21, in the undercut portions of which may be seated the heads of bolts 115 22, which bolts pass into vertical slots 23, in the edges of the platform, so as to clamp in fixed position the portable base 19 upon the movable platform section 12. The provision of the portable bases, 19 and their 120 adaptability to any location on the movable platforms through the provision of the depending ribs and the grid, permits the special machines and tools to be set approximately in the positions desired. However, 125 each special machine and tool will have as a part of the construction thereof, means for effecting an accurate adjustment so that the work performing devices upon each special machine and tool may be brought to the 130

exact position necessary for effective operation. In an application filed by Thorvald Hansen and Reimar G. F. Kurtze, October 14, 1921, Serial No. 505,737, there is disclosed a means whereby one of the special machines or tools may be adjusted and accurately positioned upon its base for performing the work for which the said machine or tool is designed.

10 As hereinbefore indicated, the movable platform is given a lateral reciprocation, so as to bodily move the special machines and tools mounted thereon into and out of operative position with reference to the line at 15 which the operations in uniting the assembled frame elements are performed. A specially constructed mechanism for reciprocating the movable platform in the manner described, as well as for actuating the work 20 performing devices of the special machines and tools, after the latter have been positioned, has been devised by me and is disclosed in an application filed Oct. 14, 1921, Serial No. 505,785, to which reference may 25 be had. Links 22' connected to the pins 15, in the line at the rear side of the platform sections, are actuated by the driving mechanism disclosed in the application last referred to. The said connecting links 22' 30 being actuated simultaneously, serve to impart the reciprocating movements to the platform sections, so that the latter are moved in unison to advance the special machines and tools to their operative positions for the performance of their progressive operations 35 during the sub-division of the time cycle allotted, and to withdraw such machines and tools upon the completion of such operations. During the retraction and while 40 the special machines and tools are at rest, the conveyor movement of the jigs to advance the work, takes place during the remainder of the allotted time cycle.

As hereinbefore stated, the upper surface 45 of the grid flush with the level of the floor, so that a smooth and unbroken surface without projections or obstructions, is provided. The space between the grid members 18 is 50 comparatively negligible, so that it will not be possible for the foot of a workman to be caught therein. Should he stand on the grid in the path of movement of the portable base, no injury to him can result, inasmuch as the portable base in the movement 55 of the platform 12, will slide over the grid and merely push him out of the position occupied. The grid constitutes a further safety device, in that it provides a protecting cover for the channel or pit 11, in which 60 the movable platform 12 operates, and thereby obviates the liability to injury to the workman, should he accidentally fall or step into the channel or pit while the platform is moving, were the channel or pit not provided with the safety grid. The grid mem-

bers 18 may be readily placed in position, and the platform and the portable base 19 mounted thereon, move free from contact with the grid construction.

The pedestal of one of the special machines or tools is designated 25 in Fig. 1. The special machines and tools are attached to the portable bases 19, and when it is desired to use any particular machine or tool, the latter, with its attached portable base 75 will be carried to its proper position with relation to the movable platform 12. The longitudinal ribs 20 of the portable base will be passed through the spaces in the grid, and the base may then be secured to the movable 80 platform in the manner hereinbefore described. This arrangement of providing each special machine or tool with a portable base of the formation described, permits such machines and tools to be very quickly 85 brought into position for use and shifted to other positions, or removed from the platform with like facility. It is not essential, however, to the successful practice of my invention that each of the reserve special machines or tools have the portable base affixed thereto, inasmuch as the results desired may be secured by first positioning the portable base upon the movable platform and then attaching the pedestal of the machine 90 or tool to the portable base. This practice, however, will require the expenditure of an additional amount of time. I may also form the depending ribs 20 as a part of the pedestal of the special machine or tool, such ribs 95 passing into the spaces of the grid and resting upon the platform sections, being secured in position as before.

Modifications may be made in the construction of the apparatus illustrated without departing from the spirit of my invention.

Having thus described my invention, what I claim and desire to secure by Letters Patent of the United States, is:

1. A grid covering a channel or pit in the floor, a movable platform reciprocating in the said channel or pit below the grid, and a machine or tool carried by the movable platform and operating above the grid, with 110 connections between the said movable platform and machine or tool.

2. A platform laterally movable in a channel or pit, a transversely arranged grid flush with the floor and covering the said channel 115 or pit, and a machine or tool adjustable as to position upon the movable platform and operating over the grid in the movements of the said platform.

3. A grid forming part of a floor, a platform movable below the grid, and a portable base for a machine or tool supported by and connected with the movable platform and operating over the grid.

4. A grid forming part of a floor, a mov- 130

able platform; a portable machine base adjustably positioned thereon, with connections between the movable platform and portable base, such connections extending in 5 the spaces of the grid.

5. An elongated platform comprising sections connected at their ends so as to move in unison, in combination with a plurality of machines or tools adjustably positioned upon 10 the said platform sections, and connections between the said machines or tools and the platform.

6. A floor portion constructed as a grid, a movable platform operating below the 15 grid, portable machine bases operating above the grid and provided with depending ribs which pass through the spaces in the grid so as to support the portable bases from the movable platform, and means for connecting the said bases to the platform.

7. A grid covering a channel or pit formed in the floor, spaced rails or tracks transversely disposed in the said channel or pit, a platform arranged therein and laterally 25 moveable over said tracks or rails and under the grid, and a machine or tool connected to the said platform and moving therewith over the grid, the connection between the platform and the machine or tool being effected through the spaces in the grid.

8. A platform composed of a plurality of sections, connections between the adjacent ends of the sections whereby the latter move as one part, a plurality of machines or tools 35 adjustably arranged on the said sections, and means for connecting the machines or tools to the platform sections.

9. An elongated platform comprising a plurality of sections, pivotal connections be- 40 tween the adjacent ends of the sections, such connections extending in lines transverse to the platform, and connections at one side of the platform sections, whereby the latter may be actuated as an integral structure, in 45 combination with a plurality of machines or tools adjustably arranged on said plat-

form and adapted to be positioned for work by the lateral movement of the platform.

10. A channel or pit construction, rails or tracks traversing the same, a laterally 50 movable platform provided with rollers guided by the rails, a grid covering the said channel or pit and enclosing the platform, in combination with a machine or tool supported above the grid, with means extending 55 in the spaces of the grid for connecting the machine or tool to the platform, to position the machine or tool for work by the movement of the platform.

11. A floor portion constructed as a grid, 60 tracks or rails thereunder, a platform movable on the tracks or rails below the grid, a machine or tool supported from the platform above the grid, and connections between the platform and machine or tool, 65 such connections being arranged in the spaces in the grid, so that the movement of the platform is imparted to the machine or tool to position the latter for the performance of its work.

70 12. A floor portion constructed as a grid, a platform movable thereunder, a machine or tool above the grid, and connections through the spaces in the grid for imparting the movement of the platform to the machine or tool to position the latter for the performance of its work.

75 13. A laterally movable platform composed of a plurality of sections, connections between the adjacent ends of the platform 80 sections such connections extending in the line of movement of the platform sections, in combination with other connections to the platform sections, whereby the said sections are moved in unison.

85 In testimony whereof, I have signed my name at Milwaukee, this 2d day of March, 1921.

B. T. ANDREN.
